UNITED STATES PATENT OFFICE.

HENRY JOHNSON, OF ARLINGTON, NEW JERSEY.

DESIGN FOR A CROWN-PLATE FOR SIGNAL-STANDS.

SPECIFICATION forming part of Design No. 29,501, dated October 18, 1898.

Application filed September 15, 1898. Serial No. 691,046. Term of patent 14 years.

To all whom it may concern:

Be it known that I, HENRY JOHNSON, a citizen of the United States, and a resident of Arlington, in the county of Hudson and State of New Jersey, have invented and produced a new and original Design for a Crown-Plate for Signal-Stands, of which the following is a specification, reference being had to the accompanying drawings, forming a part thereof.

The leading features of my design consist in a crown-plate for signal-stands having an arch form and a crown portion uprising from the body portion of the arch intermediate of the ends of the arch.

In the accompanying drawings, Figure 1 is

a view of the plate in side elevation, and Fig. 2 is a top plan view.

A represents the body portion of the plate, and B the crown uprising from the plate intermediate of its ends.

What I claim is—

The design for a crown-plate for signal-stands, substantially as shown and described.

In testimony that I claim the foregoing as my invention I have signed my name, in presence of two witnesses, this 16th day of April, 1898.

HENRY JOHNSON.
